STRIP FEEDING MACHINE

Filed May 24, 1930

UNITED STATES PATENT OFFICE

RICHARD LANGE, OF LEONIA, NEW JERSEY

STRIP FEEDING MACHINE

Application filed May 24, 1930. Serial No. 455,300.

This invention relates to a strip feeding machine or device of the nature where one or more strips of flexible material, such as metallic leaf, paper, cloth, or composition and the like is advanced or pulled to different desired lengths.

The object of the invention is to provide a simple and efficient strip or leaf pulling device in which the leaf pulling mechanism comprises a flexible belt member swingably or movably supported adjacent a driven strip pulling roll in such a manner that the surfaces of the belt and roll will be in extended contact when said roll and belt are in operative position, but will be disengaged when said belt member swings, or otherwise moves, away from the roll to readily admit of supplying new strips of stamping material or of adjusting the same. In other words, the object of my invention may be said to include the provision of means for engaging extended contact surfaces of strip pulling members and means for separating the contact surfaces of said members. I also provide means for positively driving one of said members a definite distance for the purpose of advancing the strip or stamping medium at predetermined intervals to new impress positions.

Another object includes the provision of a strip or leaf pulling device which is efficient in operation, economical of manufacture, and wherein the flexible member enfolds, to a considerable extent, the roll member so as to afford a large contact surface of the strip or leaf material, thereby avoiding breaking or tearing of said material.

Other objects will appear hereinafter and I obtain these objects by a construction illustrated in the accompanying drawing in which—

Figure 1 is a view in elevation of a strip feeding attachment or machine which is equipped with my improvement;

Fig. 2 is an end view thereof taken from the left hand side of Fig. 1;

Fig. 3 is an end view thereof viewed from the right hand side of Fig. 1; and

Fig. 4 is a diagrammatic illustration showing the relation of the strip pulling members and the path of the strip material itself.

Like numerals will refer to similar parts wherever they appear.

In my Patent No. 1,737,593 of December 3, 1929, for "Press attachments for feeding roll leaves" I have disclosed a type of apparatus for feeding a plurality of roll strips to predetermined distances at intervals of time determined by the press mechanism. In the present invention I utilize certain elements disclosed in said patent and have added thereto the means for engaging extended surface contact of the strip pulling members instead of having mere line contact. This advantage affords means for better pulling the strip medium forward without slippage or breaking the same. My invention also contemplates the use of a movable contact member whereby it is possible to disengage the contact surfaces of the feeding devices for the purpose of easily inserting new strips or for readjusting the old ones.

In the construction shown in the accompanying drawing I provide a frame 10 for supporting the strip feeding mechanism. Said frame also supports the motor and operating attachments for feeding the roll leaf a predetermined distance at suitable intervals of time determined by the printing device to which my invention is applied. Attached to either end of frame 10 are the brackets 11 and 12 fastened thereto by suitable means. At the extremity of brackets 11 and 12 there is rotatably mounted the feed roller 13.

Adjacent to the feed roller 13 in said brackets is mounted a rotatable roller 14 on a journal 15. Attached to the ends of the rotatable roller 14 are strap members 16 and 17 swingably supported therefrom. At the free ends of said straps an idler roll 18 is supported. Stretched over the idler rolls 14 and 18 is a belt or feed member of any suitable material, such as rubber, leather, or a composition material. The relation of feed roller 13 and idler rolls 14 and 18 is such that when such rolls are in position with the belt on the idler rolls said belt and the surface of the feed roll engage to a suitable extent thereby forming a greater surface engagement for the strip medium 23. In order to maintain

the flexible belt and rolls in operative position there is provided a finger 20 engaging a stop 21 (see Figs. 2 and 3) of the flange of roll 14, thereby keeping the belt in contact with the feed roll. If now it is desired to disengage the contact between the surfaces of the flexible belt and the feed roll, finger 20 is depressed and the frame, composed of straps 16 and 17 and idler roll 18, drops 10 down into position 16' shown in dotted lines on Fig. 2, thereby opening the distance between the belt surface and the roll surface for the insertion or adjustment of the strip or roll leaf material. In the construction 15 herein shown the belt member is movably supported, that is it swings away from the feed roll to vary the contact between the feed roll and the belt surfaces. In the construction herein shown but two idler rolls are 20 used to support the belt. But obviously a different construction might be employed if desired to thus support the belt.

In order to intermittently advance the feed roll 13 there is provided a pull chain 24 which 25 encircles suitable clutch mechanism (which is more fully explained in my acknowledged patent) for pulling forward the feed roll a definite distance depending on the location of the chain 24 when attached to the sector arm 25. This sector arm pivotally moves on pivot 26 when the control arm 27 is rocked by reason of the bell crank 28 being operated by the drive or friction clutch 29, which clutch is put into operation whenever the trip finger 30 releases the clutch holding disc 31 in the manner more fully described in said patent. A motor 32 is provided to operate the friction clutch through a drive mechanism comprising a set of reduction gears, represented by 33, 34, a shaft 35, and gears 36 and 37. The friction clutch is put into operation whenever the trip bar 38 is rocked to operate a toggle 39 by reason of movement of the printing platen or equivalent structure (not 40 shown) being brought into contact for making the impress and when it is desirable to move the strip material forward a definite distance to supply a fresh impress material.

What I claim as new and useful and desire 50 to secure by Letters Patent is:

1. In a strip feeding device, the combination of strip pulling members, means for holding engaged extended contact surfaces of said strip pulling members, means for separating the contact surfaces of said members, and means for positively driving one of said strip pulling members a predetermined distance.

2. In a metallic strip pulling device, the 60 combination of a roller member, and means for intermittently advancing said roller surface to a predetermined distance, a second roller member rotatively supported adjacent said first named roller member, means pivotally supported from said second roller

member, a third roller member rotatively supported in said means, and flexible means supported on two of said roller members to thereby engage the other of said roller members. 70

3. In a strip pulling device, the combination of a roller member and means for intermittently advancing said roller surface to a predetermined distance, a second roller member rotatively supported adjacent said first 75 named roller member, means pivotally supported from said second roller member, a third roller member rotatively supported in said means, a flexible belt mounted on the rotatively supported roller members, and means for locking said roller members into position for impressing said belt against the intermittently advancing roller.

4. In a strip pulling device, the combination of a roller member and means for intermittently advancing said roller surface to a predetermined distance, swingable means mounted adjacent said intermittently advancing roller, a flexible belt on said swingable means, and means for holding said belt 80 pressed onto the surface of the intermittently advancing roller. 85

5. In a strip pulling device, the combination of a roller member and means for positively driving said roller surface to a predetermined distance, swingable means mounted adjacent said positively driven roller, a flexible belt on said swingable means, means to press said flexible belt onto an extended surface of said positively driven roller, and 90 means to release such pressure. 95

6. In a strip pulling device, the combination of a driven roller member having a cylindrical surface, a movable strip holding member consisting of two rolls held in spaced end members and having a flexible surface, said rolls and end members constituting swingable means for holding said movable strip adjacent said roller member. 100

7. In a strip feeding device, the combination of a fixedly held strip pulling member having a substantially rigid surface, means for rotatably moving said member on its axis, a movable strip pulling member comprising spaced parallel rolls pivotally supported from the axis of one of the rolls and having a flexible surface for engaging an extended contact surface of the strip pulling member. 110

In testimony whereof I have hereunto set my hand on this 16th day of May, A. D., 1930. 120

RICHARD LANGE.
